No. 5,631.

Mar. 5, 1872.

UNITED STATES PATENT OFFICE.

WILLIAM MALLINSON, OF HALIFAX, ENGLAND, ASSIGNOR TO JOSEPH WILD,
& CO., OF NEW YORK, N. Y.

DESIGN FOR A CARPET-PATTERN.

Specification forming part of Design No. 5,631, dated March 5, 1872.

Specification describing a Design for Carpets, invented by Wm. MALLINSON, of Halifax, in the county of York, England.

The accompanying photographic illustration fully represents my new design.

This invention relates to several new features of ornamentation for carpets and similar fabrics; and consists, first, in a new design of the main figure or center piece A, which is octagonal, with concave sides, and with crown-shaped tufts *a* at the angles. The invention also consists in a new design for a cross-shaped figure, B, which has each of its four arms or prongs spear-shaped; also, in a new design of the quatrefoil figure C, containing a square within it. Finally, the invention consists in the new and peculiar design of foliage D,

which is interspersed between the several figures A, B, and C, as is clearly shown in the photograph.

I claim as my invention—

1. The design of the center figure A, as shown.
2. The design of the cross-shaped figure B, as shown.
3. The design of the quatrefoil C, as shown.
4. The design of the foliage D, as shown.
5. The design for a carpet consisting of the figures A B C and foliage D, as shown.

WILLIAM MALLINSON.
